US00D792491S

(12) **United States Design Patent** (10) **Patent No.:** **US D792,491 S**
(45) **Date of Patent:** **** Jul. 18, 2017**

(54) **LINEAR ACTUATOR**

(71) Applicant: **TIMOTION TECHNOLOGY CO., LTD.**, New Taipei (TW)

(72) Inventor: **Yu-Chang Lin**, New Taipei (TW)

(73) Assignee: **TIMOTION TECHNOLOGY CO., LTD.**, New Taipei (TW)

(**) Term: **15 Years**

(21) Appl. No.: **29/577,483**

(22) Filed: **Sep. 13, 2016**

(51) LOC (10) Cl. **15-09**

(52) U.S. Cl.

USPC **D15/143**; D15/148

(58) **Field of Classification Search**

USPC D12/345; D13/118, 158, 162, 184;

D15/1-5, 7, 9, 143, 148, 149, 199

CPC B66F 3/18; F16H 19/04; F16H 57/039;

H01F 7/066

(57) **CLAIM**

The ornamental design for a linear actuator, as shown and described.

DESCRIPTION

FIG. 1 is a perspective view of a linear actuator showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof; and,

FIG. 9 is a perspective view showing the linear actuator in use.

The broken lines showing portions of a linear actuator form no part of the claimed design.

1 Claim, 9 Drawing Sheets

FIG.1
